UNITED STATES PATENT OFFICE.

GEORGE H. GIBSON, OF MONTCLAIR, NEW JERSEY, ASSIGNOR TO COCHRANE CORPORATION, OF PHILADELPHIA, PENNSYLVANIA, A CORPORATION OF PENNSYLVANIA.

WATER DEAERATION.

Application filed March 24, 1922. Serial No. 546,262.

The general object of my present invention is to provide an improved method of, and apparatus for heating and deaerating feed water. More specifically, one main object of my invention is to provide an improved method of, and apparatus for heating and deaerating boiler feed water in a power plant in which there are normally available for feed water heating and deaerating purposes, a supply of exhaust steam at a pressure appreciably below that of the atmosphere, and a second source of steam at, or above atmospheric pressure. In such case I utilize steam at the low pressure available to heat the feed water up to the temperature of that steam in a jet condenser, preferably of the barometric column discharge type, from which the water is passed into a heating and deaerating apparatus of the general character of an open feed water heater in which steam at the higher pressure available is employed to heat the water to a temperature of, or slightly above 212°. In this apparatus the water is advantageously agitated as well as heated and the air liberated from the water is permitted to escape to the atmosphere through a suitable vent.

Another important specific object of my invention is to provide improved means for utilizing the water or a portion of it passed into each heating chamber for treatment therein, for cooling the air and vapor mixture withdrawn from the chamber to thereby reduce the moisture content of the mixture. This reduces the heat carried out of the apparatus by the vapor, and reduces the volume of the escaping air and vapor mixture which is of importance in some cases as it permits of the use of exhausting apparatus of smaller capacity than would otherwise be required.

By proceeding in the manner described, I am enabled to heat and deaerate water with comparatively simple and reliable apparatus, which provides, moreover, a desirable storage space for the water treated, and with an effective and economical utilization of the steam, and particularly of the steam available at low pressure, which is employed to heat the water and eliminate the air.

The various features of novelty which characterize my invention are pointed out

with particularity in the claims annexed to 55 and forming a part of this specification. For a better understanding of the invention, however, and the advantages possessed by it, reference should be had to the accompanying drawings and descriptive matter 60 in which I have illustrated and described preferred embodiments of my invention.

Of the drawings:

Fig. 1 is a diagrammatic sectional elevation; 65

Fig. 2 is an enlarged section of a portion of the apparatus shown in Fig. 1, the section being taken on the line 2-2 of Fig. 1;

Fig. 3 is a view taken similarly to Fig. 2 illustrating a modified form of the apparatus shown in Fig. 2; and 70

Fig. 4 is a section on the line 4-4 of Fig. 3.

In the construction diagrammatically illustrated in the drawings, A represents the main supply pipe for water to be treated. The pipe A discharges into the upper end of a jet condenser B of the barometric column type which preferably, as shown, is of the form in which an overflow trough C, and baffles or trays B² are arranged in the steam space of the condenser to facilitate the rapid and effective heating of the water at widely varying rates of delivery by the steam which is admitted to the steam space 85 of the condenser through an inlet B⁴. Advantageously the trays or baffles B² are enclosed by a baffle B⁵ or are otherwise so disposed that the only vapor path between the steam inlet B⁴ and the air and vapor outlet 90 piping O' leading from the condenser B is through the space between the trays or baffles B².

The overflow trough C provided is advantageously formed with special provisions adapting it for effective utilization in cooling and thereby reducing the vapor content in the air and vapor mixture, which passes out of the condenser C through the outlet piping O'. As shown the overflow trough C comprises a trough chamber C' proper with hollow side walls. In the chamber C' formed in each hollow side wall of the trough C are located a series of transverse horizontal overflow troughs C⁴ which receive water from the trough C through small orifices C⁵ which are located above the level of the bottom of the pipe A so that

the latter is water sealed. The water overflowing from the small troughs C^4 runs along the bottom wall of the corresponding chamber C^2 to an air inlet and water discharge orifice C^5 provided in the latter at one end. To facilitate the proper distribution of the water on trays B^2 the discharge orifice C^5 of one chamber C^2 is preferably located at one end of the trough 5 10 C , and the other discharge orifice C^5 is at the other end of the trough. Each chamber C^2 is separately connected to the air and vapor outlet piping O' , the connection being at the opposite end of the chamber from 15 the corresponding air inlet and water outlet C^5 .

The barometric column discharge pipe B^3 of the condenser B opens into the upper end of a second water heating and deaerating 20 device D . The latter is of the general character of an open feed water heater, and comprises an overflow trough into which the pipe B^3 discharges, and adjacent trays or baffles D^2 so enclosed by partitions D^3 , 25 or otherwise so disposed with reference to the shell of the device D , that the only vapor path from the space beneath the trays D^2 to the vent or air and vapor outlet piping D^6 opening from the top of the chamber 30 d in which the baffles D^2 are located, is through the space between the trays. The trough CA may be and is shown as identical in form with the trough C .

Advantageously the vent piping D^6 35 through which the air and vapor admixed with the air passes from the chamber d to the atmosphere includes a throttle valve F which in ordinary operation is never entirely closed, but the effective port area of 40 which may be adjusted to meet varying operating conditions. For safety purposes the vent piping D^6 may also be provided with a so-called back pressure valve FA such as is commonly employed with open feed water 45 heaters, and which is so adjusted as to open whenever the pressure in the heater D exceeds that of the atmosphere but which will check the influx of air into the heater at moments when for one reason or another 50 the pressure in the heater may become less than that of the atmosphere.

As shown the partitions D^3 are arranged 55 to pass the water leaving the chamber d on to the inclined upper portion of a baffle D^4 which, in the construction shown cooperates with the adjacent side wall of the heater D to form a conduit for carrying the water to the bottom of the water storage space in 60 the heater, adjacent a reboiler G . The latter is advantageously in the form of a manifold adapted to discharge a plurality of jets of steam into the mass of water in the lower portion of the heater, at a level substantially below that of the water level X 65 normally maintained in the heater. The

desired water level is normally maintained by means of a float N responsive to the height of water level in the heater D and controlling a throttle valve L' in the make-up water supply line L . The latter supplies 70 water to supplement the water passing to the heater D from the condenser B as required to maintain the desired accumulation of water in the heater D . In the particular construction illustrated, the pipe L 75 is connected to the discharge column B^3 adjacent the lower end of the latter. Air and vapor withdrawn from the steam space of the condenser B through the piping O' by the live steam ejector O passes through the discharge pipe O^3 of the latter into the heater D , advantageously entering the latter, 80 as shown, immediately below the lowermost baffle D^2 .

Advantageously a partition E extends 85 upward from bottom of the heater D to a height somewhat below that of the water level X thus dividing the lower portion of the water storage space in the heater D into two compartments in one of which the reboiler G is located while the water outlet D^5 opens from the other of these compartments. Advantageously one or more pairs 90 of vertical baffles E' and E^2 are interposed between the partition E and the water outlet D^5 , the baffles E' being spaced away from the bottom wall of the heater and extending to a level above the water level X while the baffles E^2 extend from the bottom 95 wall of the heater up to a level somewhat below the water level X . The baffles or partitions E' and E^2 are provided with oppositely projecting interspersed transverse baffles E^3 . This baffle and partition arrangement is provided to cause the water passing away from the reboiler over the top of the partition E to flow in a zig-zag path to the water outlet D^5 , with a resultant agitation 100 of the water which facilitates the separation from the water of the air contained therein.

As shown in the drawing, there are two 105 sources of steam supply for the reboiler G . One of these is the upper steam supply connection H which opens to the top of a valve chamber h having its lower end connected to the reboiler. Located in the valve chamber h , is a non-return valve H' advantageously provided with an operating float H^2 , the purpose of which is to prevent back flow of water through the steam connection H in case the pressure in the supply connection H falls below that in the heater D . The second steam supply connection I to the reboiler G is intended to serve as an auxiliary or supplemental supply connection and contains a regulating valve J . The valve J in the preferred construction shown is automatically actuated so as to open and close accordingly as the pressure in the 115 steam space of the heater D falls below, or 120

rises above the pressure which it is desired to maintain therein. For this purpose the stem J' of the valve J , in the construction diagrammatically illustrated, is connected 5 to the diaphragm or flexible wall K' of a pressure motor K which is in communication through the pipe K^2 with the interior of the heater D at a level above the water level X therein.

10 In the type of power plant in which my present invention is of especial utility, the main water supply pipe A leads from the discharge outlet of the hot well pump of the condenser for the main turbine unit of 15 the power plant. The steam supplied to the inlet B^4 of the condenser B may advantageously be exhaust steam from a so-called house turbine or auxiliary, the exhaust pressure of which is appreciably below that 20 of the atmosphere so that the steam passing to the inlet B^4 may be at a temperature of 160° or so. Where the plant does not comprise a house turbine or auxiliary which may advantageously supply the steam 25 needed at the desired low temperature, the steam supplied to the inlet B^4 may advantageously be taken from a low pressure intermediate stage of the main turbine.

The steam supplied to the reboiler G 30 through the inlet connection H will preferably be exhaust steam from a house turbine or auxiliary, the exhaust pressure of which is a couple of pounds or so above that of the atmosphere if the plant comprises such a house turbine or auxiliary. If 35 the plant does not comprise such an available source of steam supply to the connection H , steam may be supplied to the latter from an intermediate stage of the main turbine 40 unit adapted to furnish steam at the desired pressure. The steam supplied by the connection I to supplement, as required, that furnished through the connection H , may be live steam, or may be taken from the stage 45 of the main turbine unit in which the pressure is higher than that of the steam supplied through the connection H .

The apparatus disclosed is comparatively 50 simple and forms an effective instrumentality for heating the water in stages and effectively freeing it from air or other gases held in the water. It also provides a desirable storage space for heated water and the provision of this storage space and of the 55 baffles therein for causing the stored water to be agitated as it moves to the water outlet facilitates the liberation of the air mechanically held in the water, and the 60 liberated air may leave the water at any point in the relatively large upper surface of the water in the heater.

By heating boiler feed water in a plurality of stages, when steam is available for 65 partially heating the water at the pressure or pressures below that corresponding to the

pressure of steam at the final temperature to which the water to be heated certain known advantages are obtained. In accordance with the present invention I obtain the known advantages of heating the water in 70 stages in cases where steam for partially heating the water is available at a pressure corresponding to a temperature lower than that of the final temperature of the water in relatively simple, reliable and inexpensive apparatus which not only heats the water, but forms effective means for the liberation of air contained in the water. It will be apparent, of course, to those skilled in the art that the invention may 75 be utilized with a somewhat greater efficiency by heating the water in more than two stages, but for practical reasons I consider the simplification of the apparatus and operating conditions resulting from two stage heating of the water as compared with heating the water in a greater number of stages, to be preferable to the somewhat greater heat efficiency obtainable by heating 80 the water in a greater number of stages. 85

The special form of overflow water distributing trough C shown in Figs. 1 and 2 form an effective instrumentality for utilizing the water entering each heating chamber to cool the air and vapor mixture leaving the latter and thus reduce the vapor content 90 in the mixture. Air being a poor conductor of heat, the effective cooling of the air and vapor mixture requires an extended area of contact surface between the mixture being cooled and the cooling medium whether the latter be water sprayed through the mixture, metal cooling walls, or is otherwise constituted. With the special construction of the trough C disclosed, the air and vapor mixture passing through each chamber C^2 , traverses the broken streams of water falling from the sides of the different small troughs C^4 , and flows along 95 extended contact surfaces formed by the liquid in the bottom of the chamber C^2 and the side and top walls of the latter. While 100 adequate cooling of the air and vapor mixture requires an extended area of contact surface between the mixture and the cooling liquid or surfaces, the amount of heat to be abstracted is comparatively small, and hence it is unnecessary to pass through the troughs C^4 all of the water supplied to the 105 trough C when the apparatus is operating at full capacity, and in such a trough construction as illustrated in Figs. 1 and 2, I 110 advantageously so restrict the various ports C^3 that only a comparatively small fraction, 115 say 25% or so, of the water supplied to the trough C when the apparatus is operating at full capacity, will pass out of the trough chamber C through the ports C^3 . The 120 remainder of the water supplied to the trough C will overflow from the trough chamber C 125

over the inclined roofs of the chamber C². This gives a better distribution of water on to the baffles B² or D² when the apparatus is operating at full capacity, than would be obtained if all the water were then passed through the chambers C² and discharged on to the trays through the outlets C⁵. The fact that in the air cooler described, the passages for the air and steam mixture are 10 comparatively small in cross section and the velocity of flow of the air and vapor mixture therethrough is comparatively high, adds to the efficiency of the apparatus.

It will be apparent to those skilled in the art that the above mentioned advantages obtained with the special trough construction shown in Figs. 1 and 2 may be obtained with various other constructions, and in Figs. 3 and 4 I have illustrated one modification which may be employed for this purpose. In Figs. 3 and 4 the trough CA, replacing the trough C first described, comprises a trough chamber C¹⁰ with distributed small discharge orifices C¹¹ in its bottom wall. The aggregate capacity of the discharge ports C¹¹ may, like that of the ports C³ of the construction first described, be sufficient to discharge only 25% or so of the water entering the trough chamber C¹⁰ 20 through the pipe B³ when the apparatus is operating at full capacity. The remaining portion of the water then supplied to the chamber C¹⁰ overflows the side walls of the trough in the usual manner. The water 25 passing out of the chamber C¹⁰ through the ports C¹¹ in the bottom wall of the latter enters one or the other of two subjacent chambers C¹² which underlie the chamber C¹⁰, and are each provided at one end with a 30 water outlet and air and vapor mixture inlet C¹⁴ corresponding in location and purpose to the ports C⁵ of the construction first described. The openings C¹⁴ of the two chambers C¹² are advantageously located at opposite ends of the trough CA, and the connection between the vent piping D⁶ and each chamber C¹² is located at the opposite end of the chamber from the corresponding water outlet C¹⁴. Advantageously baffles C¹⁶ are provided on the bottom wall of the trough chamber C¹⁰ to provide a water seal about the lower end of the pipe B³. With the described construction the air and vapor mixture passing 40 through each chamber C¹² traverses broken streams of finely divided water entering the chamber through the ports C¹¹ distributed along the length of the chamber.

While in accordance with the provisions 45 of the statutes I have illustrated and described the best embodiment of my invention now known to me, it will be apparent to those skilled in the art that various changes may be made in the form of the apparatus disclosed without departing from the spirit

of my invention and that certain features of the invention may sometimes be used to advantage without a corresponding use of other features.

Having now described my invention, what I claim as new and desire to secure by Letters Patent, is:

1. The method of effectively utilizing available steam from two sources one of which is at a pressure below, and the other at a pressure above, that of the atmosphere in heating and deaerating water, which consists in first heating the water by contact with steam at the lower pressure in a chamber in which a pressure less than that of the atmosphere is maintained, and then heating the water by contact with steam at the higher pressure in a second chamber provided with an air vent to the atmosphere, and withdrawing air from the first mentioned chamber and passing it into the second chamber.

2. The method of heating and deaerating water which consists in passing the water treated first through one, and then through a second closed heating chamber so as to maintain an air and vapor space in each chamber, supplying steam to said one chamber to thereby heat the water to a temperature appreciably below 212°, passing air into said second chamber from said one chamber as required to maintain a pressure in the vapor space of said one chamber appreciably below that of the atmosphere, supplying steam to said second chamber to maintain a temperature therein above 212°, and venting air from the latter to the atmosphere.

3. Apparatus for heating and deaerating water, comprising in combination two water heaters each comprising a closed chamber with steam and water inlets and a water outlet, means for passing the water treated successively through the two heaters and so as to maintain a vapor space in each, means for supplying steam at a pressure less than that of the atmosphere to the steam inlet of the heater through which the water passes first, means for supplying steam to the steam inlet of the other heater to maintain a pressure in the vapor space of the latter above that of the atmosphere, said heater having an air vent, and means for withdrawing air from the heater through which the water goes first and passing it into the other heater.

4. Apparatus for heating and deaerating water comprising in combination a water heater of the jet condenser type with a barometric column water outlet pipe, a secondary water heater of the open feed water heater type, provided with an air vent and located below the first mentioned heater and into which said pipe opens, means for supplying steam to the primary heater, means for

supplying steam to the secondary heater, and means for passing air from the primary heater into the secondary heater.

5. Apparatus for heating and deaerating water, comprising in combination a primary water heater of the jet condenser type with a barometric column water outlet pipe, a second water heater of the open feed water heater type provided with an air vent to the atmosphere, and located below the first mentioned heater and into which said pipe opens, means for passing the water to be treated successively through the primary and secondary heaters, means for supplying steam at a low pressure to the primary heater, means for supplying steam at a higher pressure to the second heater, and means for withdrawing air from the primary heater and passing it into the second heater.
- 20 6. In water heating and deaerating apparatus, the combination with a heating chamber and provisions normally maintaining a body of water therein and a vapor space above said water, and provided with a normally submerged steam inlet, of two steam supply connections to said inlet, one from a source of steam the pressure of which varies between a pressure below and one above that which is the desired pressure in the heating chamber, and one from a source of steam at a pressure above said desired pressure, a check valve preventing back flow of water through the variable steam pressure supply connection, a valve in the other steam supply connection and operating means therefor automatically responsive to the pressure in said heating chamber for opening and closing said valve accordingly as the pressure in said chamber falls below and rises above the desired pressure.

7. In a water heater comprising a heating chamber, means for supplying water to the upper portion of said chamber and withdrawing it from the lower portion of said chamber as required to maintain the chamber partially filled with water, and means for supplying steam to said chamber to heat the water passing through the latter, the improved means for introducing water into the chamber and withdrawing air therefrom which comprises an overflow trough located in the heating chamber above the water level therein and into which the water entering the chamber is first passed, and an air cooling chamber located in the heating chamber and comprising a port for the entrance of air and vapor and the discharge of water, and an outlet port for air and vapor, and means for passing water into said cooling chamber from said trough restricted to pass only a portion of the water received by the trough when the latter is operating at full capacity.

8. Water and deaerating apparatus comprising in combination a water heating and

storage chamber in the upper portion of which a vapor space is maintained, and provided with an air outlet, means for passing the water treated through the vapor space in divided streams, a partition dividing the water storage space into a reboiling compartment into which the water passing through the vapor space enters, and an outlet compartment into which water overflows from said reboiling compartment, means for injecting steam into the reboiling compartment below the water level therein, said chamber having an outlet opening from said outlet compartment, and baffles for causing the water to flow in alternate up and down passes between said reboiling compartment and said outlet.

9. Apparatus for heating and deaerating water comprising in combination a primary water heater of the jet condenser type with a barometric column water outlet pipe, a second water heater of the open feed water heater type provided with an air vent and located below the first mentioned heater and into which said pipe opens, means for supplying steam at a pressure below that of the atmosphere to the primary heater, means for supplying steam to the secondary heater at a pressure above that of the atmosphere including provisions automatically responsive to the pressure in the secondary heater for regulating the amount of steam so supplied and means for drawing air from the primary heater.

10. Apparatus for heating and deaerating water comprising in combination a primary water heater of the jet condenser type with a barometric column water outlet pipe, a second water heater of the open feed water heater type provided with an air vent and located below the first mentioned heater and into which said pipe opens, means for supplying steam at a pressure below that of the atmosphere to the primary heater, means for supplying steam to the secondary heater at a pressure above that of the atmosphere, and a steam ejector drawing air and vapor from the primary heater and discharging it into the secondary heater.

11. In a steam power plant, means for heating and deaerating boiler feed water comprising in combination a primary water heater of the jet condenser type with a barometric column water outlet pipe, a second water heater of the open feed water heater type provided with an air vent and located below the first mentioned heater and into the upper portion of which said pipe opens, means for passing return water of condensation into the primary heater, means for supplying steam at a pressure below that of the atmosphere to the primary heater, means for supplying steam to the secondary heater at a pressure above that of the atmosphere, a make-up water supply connection opening

to said pipe at a level adjacent that at the top of the second heater, means responsive to the accumulation of water in the second heater for regulating the supply of make-up water through said connection, and means for withdrawing air from the primary heater.

12. In water heating and deaerating apparatus comprising a heating chamber, normally partially filled with water, with a vapor space above the water, and means for supplying steam to said chamber to heat the water therein, the improved means for introducing water into the chamber and withdrawing air therefrom which comprises an overflow receptacle located in said vapor space provided with an extended horizontal overflow surface, a water supply pipe dipping into said receptacle, an air cooling chamber located in said vapor space, and formed with ports providing an inlet for air and vapor, an outlet for water, an outlet for vapor and one or more passages opening from said receptacle at a level below that of its overflow surface for passing water into said cooling chamber from said receptacle, said passage or passages being restricted to pass a fraction only of the water supplied to the receptacle when the apparatus is operating at full capacity.

13. In water heating and deaerating apparatus comprising a heating chamber normally partially filled with water, with a vapor space above the water, and means for supplying steam to said chamber to heat the water therein, the improved means for introducing water into the chamber and withdrawing air therefrom which comprises an overflow trough having horizontally elongated hollow side walls over which the water may overflow, each hollow side wall comprising an air cooling chamber provided with a bottom port admitting air and vapor and discharging water, and with an outlet port for air and vapor, and with water inlet ports opening from said trough below its overflow edges and restricted to pass less than the total amount of water entering the trough when the apparatus is operating at full capacity, and a water sealed pipe dipping into said trough for supplying water to the latter.

14. The method of utilizing steam bled from a steam turbine at different pressures in heating and deaerating water which consists in first heating the water by contact with steam bled from the turbine at a lower pressure in one chamber, then further heating the water by contact with steam bled from the turbine at a higher pressure in a

second chamber and subjecting the water to a vigorous scrubbing action in one of said chambers, passing air liberated from the water in one of said chambers into the other chamber, and withdrawing air from the last mentioned chamber.

15. The method of heating and deaerating water which consists in passing the water successively through a plurality of heating chambers each of which contains a steam space through which the water is passed in divided form, supplying steam to the two chambers so as to maintain a substantially higher pressure in the steam space of the chamber through which the water passes last than in the steam space of the chamber through which the water passes first and so as to subject the water to intimate contact with steam in each of said chambers and to a vigorous scrubbing action in one of said chambers, passing air liberated from the water in one of said chambers to the other chamber and withdrawing air from the last mentioned chamber.

16. Apparatus for heating and deaerating water comprising two heating chambers and connections for passing the water to be heated successively through the two chambers, a connection between said chambers through which air and vapor may pass from one chamber into the other, means for withdrawing air from the last mentioned chamber, and means for bringing steam into contact with the water in each chamber in such manner as to maintain an appreciably higher steam temperature in one chamber than in the other, said last mentioned means including means for subjecting the water to a vigorous scrubbing action by the steam in one of said chambers.

17. Apparatus for heating and deaerating water comprising two heating chambers and connections for passing the water to be heated successively through two chambers, a connection between said chambers through which air and vapor may pass from one chamber into the other, means for withdrawing air from the last mentioned chamber, means for maintaining different steam pressures in the two chambers including a separate turbine bleeding connection to each chamber, and means in one of said chambers for subjecting the water to a vigorous scrubbing action by the steam admitted to said chamber.

Signed at Philadelphia in the county of Philadelphia and State of Pennsylvania this twenty first day of March A. D. 1922.

GEORGE H. GIBSON.
